UNITED STATES PATENT OFFICE.

JOHN D. BOWNE, OF NEW YORK, N. Y., ASSIGNOR, BY MESNE ASSIGNMENTS, TO
ELEVATOR SUPPLY AND REPAIR COMPANY, A CORPORATION OF ILLINOIS.

ELEVATOR SIGNAL SYSTEM.

1,132,552.

Specification of Letters Patent. Patented Mar. 23, 1915.

Application filed July 25, 1903. Serial No. 168,952.

To all whom it may concern:

Be it known that I, JOHN D. BOWNE, a citizen of the United States, and resident of New York, in the county of New York and 5 State of New York, have invented certain new and useful Improvements in Elevator Signal Systems, of which the following is a specification.

This invention relates to improvements in 10 elevator signal systems, and its main object is to provide an effective signal system of this class in which the controlling parts are so located, and coöperate with one another in such a manner, that they are not as liable 15 to get out of order as the corresponding elements of systems heretofore used.

One of the principal features of my invention is the location of the principal controlling devices at a fixed point with respect to 20 the elevator shaft or shafts, at which point the controlling elements are so assembled that they can be readily got at for inspection, adjustment and repair. Because of their location in such position the use of the 25 ordinary sliding controlling elements or contacts is dispensed with, the general organization of the system simplified, and substantially all of the movable parts governing the 30 operation of the system and on which the proper working of the system depends, are grouped at a point where all the parts are easily accessible.

Another important feature which distinguishes my improved elevator signal system 35 from others with which I am familiar is the employment of positively acting mechanical controlling devices for operating electrical circuit controllers which govern the signal circuits. These mechanical devices are preferably operated by elements governed directly by the movements of the elevators, and the principal controlling member will usually have a to-and-fro movement in a given path, such movement corresponding to the 40 up and down movement of the elevator by which it is governed. Separate controlling members are preferably employed for governing the operation of "up" and "down" floor-signal-controllers each of which will be 45 mechanically set and reset to make and break the circuit to its signal at the proper points in the movements of the corresponding elevator. Where more than one elevator is employed, as is usually the case, several controlling members or pairs of controlling ele- 50

ments, may be employed with a plurality of circuit or floor-signal-controllers or pairs of floor-signal-controllers in order that the "up" or "down" signal, as the case may be, may be given to that one of the series of elevators which is nearest the desired floor and is moving in the proper direction. 60

Other features of my invention not hereinbefore referred to will be hereinafter described and are illustrated in the accompanying drawings, in which— 65

Figure 1 is a side view of an elevator and its shaft and operating means, together with a coöperative signal apparatus embodying my invention. Fig. 2 is a front elevation of 70 the same, with some of the parts removed for the sake of clearness. Fig. 3 is an enlarged sectional plan of a portion of the signal controlling apparatus. Fig. 4 is an enlarged side elevation of one element of the signal 75 system, and also illustrates diagrammatically the calling and signal circuits. Fig. 5 is an enlarged detail illustrating the main controlling member of the mechanism and its operating means. Fig. 6 is a detail of a 80 resetting device. Figs. 7 and 8 are details illustrating in plan a modification of the invention. Fig. 9 is an edge view of said modification. Figs. 10, 11 and 12 are details illustrating in perspective various parts of 85 such modified construction. Fig. 13 is a detail of a portion of the main mechanism.

Similar characters designate like parts in all the figures of the drawings.

Referring first to Figs. 1 and 2, it will be 90 seen that I have illustrated an elevator movable in a shaft which intersects three floors, designated respectively by 1, 2 and 3. The fourth floor, designated by 4, carries the means for supporting the elevator 5, and as 95 shown herein embodies the usual sheave 6, on which the supporting cable 7 is wound up or from which it is unwound, this sheave serving to operate through suitable transmitting means, the main controlling member 100 corresponding to its elevator. The transmitting means illustrated herein consists of a pinion 8 on the axis 10 of the sheave 6, this pinion being movable in unison with said sheave, and a spur gear 9 in mesh with 105 said pinion and mounted in this case for rotation at one end of a bracket 11, which may be secured to the pillow-block 12 by which the shaft 10 is supported. This pinion is normally held in place by the spring 110

8', the tension of which is adjustable by a nut 8''. A small band-wheel 13, mounted on the same axis as the gear 9 and movable in unison therewith, may transmit the "up" 5 or "down" movement of the elevator to the main controlling member of the signal system through a band or belt 14, which in this case passes over guide pulleys such as 15 and 16 and operates a driven pulley, such 10 as 18, which in turn is fastened to one end of the driven shaft 19 by which movement is transmitted directly to the controlling member. In Fig. 1 three of these driven pulleys 18, 18' and 18'' are illustrated, and 15 they govern the movements of three separate controlling members, one for each of the three elevators which are assumed to make up the system shown. These driven pulleys 18, 18' and 18'' with their driven 20 shafts, such as 19, etc., are located at a fixed point with respect to the elevator shafts, in this case on the floor 4 above all of the elevator shafts, and the pulleys 18, 18' and 18'' are preferably rotatable in different vertical 25 planes so that the bands or pulleys 14, etc., (it being understood that a separate band is used for each elevator and its driven pulley 18, etc.,) will not interfere with one another. Any suitable upright, such as that shown at 30 20, may support the driven pulleys 18, etc., this upright having secured thereto a plurality of bracket-arms 21, each of which has a pair of bearings such as 22 and 23, in which is journaled the shaft 19 hereinbefore 35 referred to. Immediately in advance of the bearing 23 the shaft 19 has a bevel gear 25 which in this case meshes with a similar bevel-gear 26 secured to a short shaft 27 journaled in the bearing 28 at the inner end 40 of a lateral extension 21' of the main bracket 21. This gear 26 and its short shaft 27 constitute in the present construction means for directly operating the principal mechanical controlling member governed by a 45 corresponding elevator, and this controlling member is here shown as a rotary arm 30 keyed to the shaft 27 and held in place by a check-nut 31. At its free end, as it swings in a circle in one direction or the 50 other as the corresponding elevator is moved up or down, the arm 30 has one or more members or elements for mechanically operating one or more floor-signal-controllers or pairs of floor-signal-controllers. Preferably the arm 30 has two such controlling 55 elements, designated herein by 35 and 36, the former of which is operative on the upward movement of the elevator and the latter on the downward movement. Each of 60 these controlling elements is preferably in the form of a by-pass device, the two parts being so mounted as to have by-pass movements in opposite directions. The two by-pass elements, 35 and 36, are pivoted at the 65 outer end of the arm 30 and normally move

in unison therewith and are held in their normal positions by springs, such as 37 and 38, which press the elements 35 and 36 into engagement with stops, one of which is shown at 35'' as a stop-pin.

The arm 30 with its two controlling elements 35 and 36 for governing the "up" and "down" signals respectively, travels in such a path as to coöperate with a pair of intermediaries, such as tappets 40 and 41, 70 secured to spindles 42 and 43 mounted for oscillation in any suitable manner. These spindles are preferably supported at their ends by needle bearings such as 44, one of which rises from a base-plate 45, while the 80 other may be carried by a bracket 46 (see Fig. 1) fastened to the upper end of a vertical post 47 fastened at its lower end to the plate 45. The upper bearings for both of the spindles 42 and 43 are carried by this 85 bracket 46. Stops, such as 48, in position to engage arms, such as 49, fastened to the spindles 42 and 43, may determine the normal positions of said spindles, and springs such as 50 may hold these parts in such normal positions and return them thereto after being operated.

The arm 49 in addition to constituting a stop for limiting the return movement of the spindle 42 about its axis (see Fig. 4) also 95 coöperates at its inner end with one element of a circuit-controller or floor-signal-controller and serves to reset the same after such floor-signal-controller has been released or set by the usual push-button or 100 other device operated from the floor to which such controller corresponds, a suitable stop 66' being shown in Fig. 4 for limiting the return movement of the floor-signal controller. In this construction I have 105 illustrated a well-known drop device for releasing or setting the floor-signal-controller, two of such drop devices being employed in connection with the two spindles 42 and 43 and their associated parts, although as one 110 of these devices is directly behind the other in Fig. 4 only one of these shows. The electromagnet 51 of one of these drop devices is in circuit in this case with a push-button 52, while the electromagnet of the other is controlled by the second push-button 53, these 115 two push-buttons and magnets controlling the "up" and "down" floor-signal-controllers, the circuit-making element of one of which is shown at 54 while the corresponding element of the other controller is indicated at 55. Each of the elements 54 and 55 is a two-armed circuit-maker, the arms of which are adapted to dip into corresponding mercury electrodes, such as 60 120 and 61.

When the button 52 is pressed the armature 51' of the drop device of the floor-signal-controller 54 which governs the "up" movement of the elevator is attracted, and 130

the detent 65 releases the drop-shutter 66, the weight of the shutter and its connections with the circuit-controller 54 causing all these connected parts to drop, and the circuit to be made at the mercury electrodes 60. It will be noticed that each of the circuit-making elements of the floor-signal-controllers is electrically separated from all mechanical controlling parts by insulation, such as 67.

The making of the circuit at the "up" electrodes 60 causes the corresponding circuit to be closed to the "up" signal of the floor represented by the "up" floor-signal-controller, in this case the switch 54. The "up" and "down" signals are preferably a white light such as 70 and a red light such as 71, the circuit to the red light being closed in a manner analogous to that just described whenever the button 53 is pressed to release the drop device controlling the break at the electrodes 61.

Whenever an elevator responds to a signal the circuit of such signal should be automatically broken as soon as the car reaches the proper point in its further movement in the elevator shaft. The principal use of the main controlling member 30, which has a movement corresponding to that of its elevator, is to reset the floor-signal-controller after an elevator has stopped in response to the signal and has passed beyond the same. If, for example, the car controlling the arm 30 receives the signal to stop either on its up or down trip, the corresponding "up" or "down" element 35 or 36 carried by said arm 30 will engage the tappet 40 or 41, as the case may be, and will oscillate the spindle 42 or 43 according as the elevator is moving up or down. The rocking of the tappet 40 and its shaft 42 causes the inner end of the arm 49 to engage the drop-shutter 66 and force the same mechanically back to its original position, into engagement with a stop, such as the stop-pin 66', in which position it is latched by the detent 65, this operation serving to break the circuit between circuit-controller 54 and the electrodes 60. In a similar manner the drop-shutter controlling the circuit at the electrodes 61 is reset and the circuit broken if the same car is descending. In this case the controlling element 36 governing the downward movement will rock the tappet 41 and its spindle 43 and reset the shutter of the other drop device. When the arm 30 rotates in the direction of the arrow, as seen in Fig. 3, it controls the resetting of the "up" floor-signal-controller, and when it rotates in the reverse direction it operates to reset the "down" signal controller. When moving in the direction of the arrow in Fig. 3 the controlling element 35 is a fixed element and moves with the arm 30, but the element 36 at this time constitutes a by-pass device and

passes by the tappet 41 without operating it. When the arm 30 is moving in the reverse direction, however, the controlling element 36 is a fixed member moving in unison with the arm 30 and oscillates the tappet 41, while the element 35 swings relatively to the arm 30 and passes by the tappet 40 without operating the same.

The number of floor-signal controllers used in any given embodiment of my system will of course depend upon the number of floors at which the elevator is to make stops. In these drawings three sets of floor-signal-controllers and resetting devices therefor are shown, as the elevators shown in Figs. 1 and 2 make stops at three floors. These sets of devices, when so organized as to co-operate with rotary controlling members, are arranged in a circuit and spaced at intervals corresponding to the distances between the floors of the building, and are also placed successively in such circuit and properly adjusted with respect to the initial position of each rotary controlling member. The number of controlling members, such as 30, which will be used, will be governed entirely by the number of elevators in the building; and hence the number of pairs of tappets on the oscillatory resetting spindles will correspond to the number of arms 30 and the number of elevators used.

In Figs. 7 and 8 I have illustrated a modification of my invention for the purpose of adapting the same for use in elevator systems in which it is desired to run one or more of the cars as an express elevator. The devices hereinbefore described are not adapted for use on express elevators for the reason that the by-pass resetting devices carried at the ends of the rotary controlling members move constantly in the paths of the tappets carried by the vertical shafts which control the resetting of the circuit-breakers 54, etc., to their normal positions. In order that such a system may operate properly when used in connection with an express elevator it is necessary to provide some means for throwing one of the co-operative elements by which the resetting operation is controlled, out of operative relation with its coacting member when the elevator is running on an express schedule, the parts being preferably so organized as to permit any elevator to be run either as an express or as a local, in which case the resetting element or elements corresponding to such elevator should be so constructed as to be movable into and out of operative relation with a coacting part, so that the floor-signal-controllers will be reset if the elevator is running as a local but will not be affected if it is running as an express.

The construction which I prefer to employ is similar in most respects to that before described, the main controlling mem-

ber being designated by 30' and being mounted at one end of the bracket 21" so as to make one substantially complete turn, in the plane of said bracket, from one edge 5 of the bracket to the other, and another substantially complete turn in the other direction back to its original position when the movement of the elevator is reversed. At the free end thereof the controlling member 30' has a shiftable element or plate 80 preferably movable lengthwise of the arm 30', and on this shiftable element controlling elements 35' and 36' may be pivoted substantially in the same manner as the corresponding elements 35 and 36. These controlling elements 35' and 36', however, being mounted on the shiftable element 80 instead of on the arm 30' will be movable lengthwise of such arm, and hence their radius of movement may be increased or diminished according as it is desired to cause them to travel operatively or inoperatively. These arms 35' and 36' are preferably by-pass elements which will operate coacting tappets (such as 40 and 41) when moving in one direction or the other but will pass by such tappets on their return movements. These controlling elements may be held in place by suitable springs, such as 38'. The shiftable element 80 is pivoted at 81 and may be shifted against a suitable stop by means of a spring 82. This stop may be the inner end wall of a slot 80" in which the pivot-pin 180 of the by-pass devices 35' 30 and 36' works, this pin passing through an opening 80''' in the plate 80. In the present construction this spring serves to draw the shiftable element inward and with it the controlling elements 35' and 36', but the normal position of said shiftable element 80 is that shown in full lines in Figs. 7 and 8, in which position the parts 35' and 36' are in position to coöperate properly with the tappets and reset the circuit-breakers.

For the purpose of retaining said shiftable element 80 and the controlling elements 35' and 36' in said normal positions and preventing the spring 82 from shifting them to an inoperative position, I prefer to employ a mechanical detent which may be operated mechanically each time that the arm 30' arrives at one end of its path of movement; and for the purpose of releasing said detent 50 I prefer to employ an electrical controlling device which may be operated whenever it is desired to run the elevator controlling the arm 30' as an express. In this construction I have illustrated at 83 and 83' a pair of separated insulated contacts connected to wires 84 and 85, which, with a source of energy or battery *b* and a switch 86 constitute one side of an electrical circuit. This circuit is completed at one end of the path of movement 60 of the arm 30', preferably by means of a

pair of spring contact-arms 87 and 88 connected respectively to the terminals of an electromagnet 89. When these contact-arms engage the contacts 83 and 83', as shown, a circuit will not usually be completed, because the switch 86 will normally be open. If, however, this switch is closed, as shown in Fig. 8, the circuit will be completed, the magnet 89 will be energized and its armature will be attracted. This armature carries a detent 70 90 which normally is down and away from the poles of the magnet and in this position latches the shiftable element 80 in the position shown in full lines, but if the circuit is complete the detent 90 will be attracted and 80 the spring 82 will draw the element 80 to the position shown by dotted lines in Fig. 9, when the elevator may be run as an express without affecting the floor-signal-controllers. Whenever the circuit is broken at the switch 86 85 the shiftable element 80 will be reset to its operative position, this being preferably accomplished by providing said member with a cam-face 180 which at one end of the path of movement of the arm 30' comes into contact with a suitable operating device such as the antifriction roll 91 carried by the bracket 21", and is returned to its normal operative position. It will be noticed that the roll 91 operates the shiftable element 80 95 in this manner at one end of each movement of the arm 30' regardless of the position of the switch 86, but if the electromagnet 89 is energized the detent 90 will of course be out of the path of the element 80 and the spring 100 82 will be effective to shift said element to the dotted line position.

What I claim is:

1. In a signaling apparatus for elevators in combination, a shaft and car, an electrically-operated visual signal for the operator, a switch in the circuit to said signal, a detent for holding said switch in open position, a magnet and switch for releasing said detent, and restoring mechanism comprising a movable restoring device moved correspondingly with but much slower than said car and an intermediate normally stationary but slightly movable portion adapted to be engaged and moved by said restoring device, when moving in one direction, to mechanically move said switch to open position where it will be engaged by said detent, and in the other direction, when said restoring device moves in the opposite direction, 110 without moving said switch.

2. In a signaling apparatus for elevators in combination, a shaft and car, an electrically-operated visual signal at each floor, a switch corresponding to each floor in the circuit of the corresponding signal, a detent corresponding to each floor for holding its respective switch in open position, a magnet and switch corresponding to each floor for releasing the corresponding detent, and re. 125 130

- storing mechanism comprising a movable restoring device moved correspondingly with but much slower than said car and an intermediate normally stationary but slightly 5 movable portion corresponding to each floor adapted to be engaged and moved by said restoring device, when moving in one direction, to mechanically move its switch to open position where it will be engaged by its 10 detent, and in the other direction, when said restoring device moves in the opposite direction, without moving said switch.
3. In a signaling apparatus for elevators in combination, a shaft and car, a signal, a 15 movable signal-controlling part and a detent for holding said part in position to render the signal undisplayed, a magnet and switch for releasing said detent and thereby releasing said signal-controlling part and 20 causing the signal to be displayed, and restoring mechanism comprising a movable restoring device moved correspondingly with but much slower than said car and an intermediate normally stationary but slightly 25 movable portion adapted to be engaged and moved by said restoring device, when mov-
- ing in one direction, to mechanically move said signal-controlling part to its detent-engaged position, said signal being canceled by such movement. 30
4. In an elevator signal system, the combination with a floor-signal-controller, of means for operating said floor-signal-controller, a movable controlling member located in a given position with respect to the 35 elevator shaft and controlled in its movements by the travel of the elevator, a resetting intermediary in the path of and governed by said controlling member and operative for resetting said floor-signal-controller, and means between said controlling member and the resetting intermediary for preventing the operation of the latter on the return movement of the former. 40
- Signed at New York in the county of New 45 York and State of New York this 16th day of July A. D. 1903.

JOHN D. BOWNE.
